BEAD STRAND FOR A CURTAIN ELEMENT
OR THE LIKEIrving Levine, 5212 Weller Drive,
Woodland Hills, Calif. 91364

Filed Mar. 7, 1969, Ser. No. 16,110

Term of patent 14 years

The term of this patent subsequent to Aug. 6, 1985,
has been disclaimed

Int. Cl. D6—10

U.S. Cl. D6—205

FIG. 1 is a top plan view of a bead strand for a curtain element or the like showing my new design in which two repeat units are illustrated;

FIG. 2 is a side elevational view thereof; and

FIG. 3 is an end view taken along line 3—3 of FIG. 1.
I claim:

The ornamental design for a bead strand for a curtain element or the like, as shown and described.
